(57) **CLAIM**

The ornamental design for an adjustable tension device, as
shown and described.

DESCRIPTION

FIG. 1 is a front, perspective view of an embodiment of an
adjustable tension device.

FIG. 2 is a front view of an embodiment of an adjustable
tension device.

FIG. 3 is a rear view of an embodiment of an adjustable
tension device.

FIG. 4 is a first side view of an embodiment of an adjustable
tension device.

FIG. 5 is a second side view of an embodiment of an
adjustable tension device.

FIG. 6 is a top view of an embodiment of an adjustable
tension device.

FIG. 7 is a bottom view of an embodiment of an adjustable
tension device.

FIG. 8 is a front, perspective view of a second embodiment
of an adjustable tension device.

FIG. 9 is a front view of a second embodiment of an
adjustable tension device.

FIG. 10 is a rear view of a second embodiment of an
adjustable tension device.

FIG. 11 is a first side view of a second embodiment of an
adjustable tension device.

FIG. 12 is a second side view of a second embodiment of an
adjustable tension device.

FIG. 13 is a top view of a second embodiment of an
adjustable tension device.

FIG. 14 is a bottom view of a second embodiment of an
adjustable tension device.

FIG. 15 is a front, perspective view of a third embodiment
of an adjustable tension device.

FIG. 16 is a front view of a third embodiment of an
adjustable tension device.

FIG. 17 is a rear view of a third embodiment of an adjustable
tension device.

FIG. 18 is a first side view of a third embodiment of an
adjustable tension device.

FIG. 19 is a second side view of a third embodiment of an
adjustable tension device.

FIG. 20 is a top view of a third embodiment of an adjustable
tension device.

FIG. 21 is a bottom view of a third embodiment of an
adjustable tension device; and,

FIG. 22 is a front, perspective view of a third embodiment
of an adjustable tension device attached to an exemplary
(unclaimed) holster.

The broken lines in the drawings depict unclaimed subject
matter only and form no part of the claimed design.
